UNITED STATES PATENT OFFICE.

BURNS LYMAN SMITH, OF SYRACUSE, NEW YORK.

ONE-PIECE CAST-METAL WHEEL AND METHOD OF MAKING THE SAME

1,401,502.

Specification of Letters Patent. Patented Dec. 27, 1921.

Application filed June 8, 1917. Serial No. 173,538.

To all whom it may concern:

Be it known that I, BURNS LYMAN SMITH, a citizen of the United States, and a resident of Syracuse in the county of Onondaga and State of New York, have invented a certain new and useful One-Piece Cast-Metal Wheel and Method of Making the Same, of which the following is a specification.

This invention relates to cast metal wheels, and has for its object a simple and efficient construction whereby distortion due to unequal expansion and contraction of parts of the wheel is reduced to a minimum, and it consists in the novel features herein-after set forth and claimed.

In describing this invention, reference is had to the accompanying drawings in which like characters designate corresponding parts in all the views.

Figure 1 is a side elevation, partly broken away and in section, of a wheel embodying a preferable form of my invention.

Fig. 2 is a sectional view on line 2—2, Fig. 1.

This cast metal wheel is usually composed of a single piece and is formed at intervals with outwardly extending slots for preventing distortion during expansion and contraction of the wheel while being manufactured. Each slot is open at one end, and usually at both ends.

1 designates a hollow, cast one piece wheel of the type described in my Patent No. 1,178,959, April 11, 1916. This wheel preferably comprises a hollow hub portion 2, a hollow rim portion 3, and spokes 4, one of said portions, as the hub 2, being provided with slots 5 extending outwardly in substantially radial directions from the central opening of the hub. The slots 5 usually extend entirely through the hub and divide the same into segments, the lines of division between the segments extending between some of the spokes.

45 The hollow hub 2 may be provided with suitable reinforcing webs 6 and the hollow rim with radially extending webs 7 as in my above-mentioned patent.

8 designates the segments into which the hub is divided by the slots 5, and usually the segments are provided at their ends with walls 9 on opposite sides of the lines of division, that is, at opposite sides of the slots 5, although these walls 9 may be wholly or partly omitted.

A wheel constructed as described is par-

ticularly advantageous, because after it has been cast there is a minimum necessity for exercising care preliminary to and during its final heat treatment.

What I claim is:

1. A wheel having spokes and rim and hub portions rigid with the spokes, one of said portions being cast in one piece and the other divided at intervals along lines extending toward its center, the lines of division extending entirely through said portion whereby said portion is divided into sections separated at all points from each other, substantially as and for the purpose specified.

2. A one piece wheel having spokes and rim and hub portions rigid with the spokes, one of said portions being divided at intervals along planes extending in substantially radial directions and intersecting the inner and outer circumferential faces of said portion and thereby dividing said portion into segments which are separated from each other, substantially as and for the purpose set forth.

3. A hollow cast metal wheel having a hub provided with slots extending outwardly from its central opening and opening through the outer circumference of the hub thereby dividing the hub into segments, substantially as and for the purpose described.

4. A one piece cast metal spoke wheel having a hub integral with the spokes, the hub being divided into segments along planes extending in substantially radial directions between the spokes, substantially as and for the purpose specified.

5. A cast metal wheel having integral rim, hub and spokes, the hub being divided between the spokes into segments, substantially as and for the purpose set forth.

6. A one piece cast metal wheel having integral hollow rim, hub and spokes, the hub having slots extending outwardly from its central opening and between the spokes, substantially as and for the purpose specified.

7. A cast metal wheel having a hollow rim and hub portions, one of said portions being provided with slots extending toward the center of the wheel, said portion having opposing walls on opposite sides of the slots, substantially as and for the purpose set forth.

8. A one piece cast metal wheel having spokes and hollow rim and hub portions, one of said portions being divided along

substantially radial lines into segments, and the segments having opposing walls located on opposite sides of the lines of division between the segments, substantially as and for the purpose described.

9. A one piece cast wheel having spokes, a rim and a hollow hub, the hub being divided along substantially radial lines into segments, and the segments having end walls

at their ends opposed to the end walls of the adjoining segments, substantially as and for the purpose specified.

In testimony whereof, I have hereunto signed my name, at Syracuse, in the county of Onondaga, and State of New York, this 16th day of June, 1917.

BURNS LYMAN SMITH.
